FAT-SOLUBLE VITAMIN ESTER
CONCENTRATION PROCESS

Loran O. Buxton, Newark, N. J., assignor to National Oil Products Company, Harrison, N. J., a corporation of New Jersey

No Drawing. Application July 13, 1942,
Serial No. 450,761

9 Claims. (Cl. 167—81)

This invention relates to a process for producing vitamin concentrates, and more particularly to an improved process for preparing concentrates of fat-soluble vitamin esters.

One of the well known methods of preparing fat-soluble vitamin concentrates involves the saponification of the fatty material present in fat-soluble vitamin containing oils and recovering the unsaponifiable matter from the saponified mass by a suitable solvent. This process has several disadvantages among which there may be mentioned the concentration with the vitamins of many undesirable tastes and odors present in the original oil, thus producing a vitamin concentrate which is rather objectionable in these respects. Furthermore, such concentrates consist primarily of vitamin alcohols, which are less stable towards oxidative deterioration than are the corresponding natural vitamin esters.

In order to produce concentrates of the vitamins in their natural ester forms, the process which is disclosed and claimed in copending application of Dombrow, Serial No. 343,558, filed July 2, 1940, was developed. In that process a vitamin-containing oil is contacted with an organic polar solvent which is substantially miscible with fatty materials at temperatures substantially above room temperature and partially immiscible therewith at temperatures substantially below room temperature; and thereafter cooling the solvent-oil solution to a temperature substantially below room temperature whereby a substantial portion of the oil separates from the solution. The soluble fraction which remains in the polar solvent has a much higher fat-soluble vitamin content than the portion which is insoluble in the solvent. The vitamins present in the highly potent fraction are in their naturally occurring ester form. Such concentrates which are much more potent than the original oil, have found wide uses in the vitamin field. However, the concentrates which are produced by that process do have certain disadvantages. The solvent extraction, in addition to concentrating the fat-soluble vitamins, also concentrates therewith a large portion of the coloring matter originally present in the oil, as well as the free fatty acids and also many of the malodorous and ill-tasting constituents of the oil. A further disadvantage of this process is that many oils contain certain constituents, e. g., free fatty acids, saturated and slightly saturated triglycerides including stearins, etc., which tend to entrap the solvent which is being employed to extract the vitamins. As a result thereof, the efficiency of the extraction

process is somewhat decreased and the yield of vitamin A is much lower than what it would be if no solvent were entrapped in the oil immiscible with the solvent at the low temperature. Also, because of the great bulk of the material being treated, large volumes of solvent and much equipment are required.

In my copending application, Serial No. 450-757, filed concurrently herewith, there is disclosed and claimed a process for producing highly potent concentrates of esters of fat-soluble vitamins by selectively saponifying (hydrolyzing) a fat-soluble vitamin-containing marine oil. By carrying out the saponification of a marine oil under the conditions disclosed in said application, it is possible to hydrolyze up to about 50% to 60% of the glycerides in the oil without splitting any substantial amount of the fat-soluble vitamin esters, whereby the resulting unsaponified fraction contains the vitamins primarily in their ester form.

It is the object of this invention to provide an improved process for the preparation of fat-soluble vitamin ester concentrates.

A further object of the invention is to provide an improved process for the preparation of concentrates of vitamin A and D esters.

Another object of the invention is to provide concentrates of fat-soluble vitamins which are substantially devoid of free fatty acids and undesirable tastes and odors.

Another object of the invention is to provide highly potent concentrates of fat-soluble vitamins wherein the vitamins are substantially all present in the naturally occurring ester form.

Other objects of the invention will in part be obvious and will in part appear hereinafter.

I have discovered that the above and other objects of the invention may be realized by saponifying 10% to 60% of the glycerides in a fat-soluble vitamin-containing marine oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature and separating the solvent solution of the vitamins thus extracted from the remainder of the unsaponified fraction.

Contrary to the general belief, I have found that in partially saponifying a fish or fish liver oil the saturated and slightly unsaturated triglycerides, hereinafter referred to as "saturated

glycerides," are selectively saponified, i. e. these saturated glycerides take precedence over unsaturated glycerides and other saponifiable matter, except free fatty acids, in order of reaction with alkali or alkaline agents. This result may be due to the fact that in marine oils the unsaturated triglycerides have higher molecular weights than the more saturated glycerides present therein. Moreover, as shown in the curve comprising the drawing in the aforesaid application filed concurrently herewith, the vitamin esters do not react with alkali to any substantial degree until the oil has been saponified beyond about 75% or 80%.

The invention accordingly comprises the several steps and relation of one or more of such steps with respect to each of the others, and the product possessing the features, properties and the relation of elements, which are exemplified in the following detailed disclosure, and the scope of the invention will be indicated in the claims.

In carrying out the process of this invention, any fat-soluble vitamin-containing marine oil may be used including, *inter alia*, cod liver oil, shark liver oil, tuna liver oil, halibut liver oil, mackerel liver oil, ling cod liver oil, sole liver oil, spear fish liver oil, sword fish liver oil, herring oil, sardine oil, whale liver oil, seal liver oil, etc.

As aforementioned, the first step in the process of the invention involves partial saponification of a fat-soluble vitamin-containing marine oil. The degree of saponification of the oil may be varied depending upon the type of concentrate desired. Good results are obtained when an amount of alkali sufficient to saponify from about 10% to about 60% of the glycerides present in the fatty material is employed, the preferred range, however, being from about 30% to about 50%.

The partial saponification eliminates from the unsaponified oil substantially all the free fatty acids and a large amount of the coloring matter and undesirable tastes and odors originally present therein and at least a major portion of the saturated glycerides. In carrying out the partial saponification step by means of an alkaline agent it is preferred to employ potassium hydroxide, it being understood, however, that any suitable alkaline agent may be used in lieu of potassium hydroxide such as sodium hydroxide, sodium carbonate, potassium carbonate, etc.

In order to produce the most satisfactory and most highly potent ester concentrate, it is preferred to carry out the saponification of the fatty material in such a manner that the glycerides will be selectively hydrolyzed, leaving the vitamin ester unattacked. The principal conditions which are necessary to obtain the desired selectivity are fully disclosed in my copending application, Serial No. 450,757, referred to *supra*. However, in general, conditions which are conducive to selective saponification are relatively low temperatures, e. g., room temperature, carrying out the saponification in the presence of an inert solvent such as a hydrocarbon or halogenated hydrocarbon solvent, e. g., heptane, hexane, petroleum ether, ethylene dichloride, methylene chloride, trichloroethylene, etc., and employing a somewhat less concentrated alkali than is usually employed in conventional saponification procedures. When the saponification is carried out in the presence of an inert solvent, the solvent preferably comprises from about 15% to about 99% based on the weight of the oil and preferably the solvent should comprise about 25% to about 75% based

on the weight of the oil. In most saponification procedures, a saponification catalyst, e. g., isopropanol, is employed to accelerate the reaction. Elimination of the use of such catalysts or a reduction of the amount thereof to about 1/2% to 1% based on the weight of the oil when no non-polar solvent is used will also aid in making the saponification more selective. It is to be understood that it is not necessary to carry out the saponification step in the presence of either a catalyst or solvent medium.

After the fatty material has been partially saponified, the unsaponified fraction, hereinafter termed the "semi-concentrate," is separated from the soaps and glycerine by any suitable means, e. g., solvent extraction, centrifugation, etc. If the saponification has been carried out in the presence of an inert solvent, and it is desired to separate the unsaponified material from the soaps by means of solvent extraction, it is preferred to extract with the same solvent that was employed during the partial saponification step. The semi-concentrate may readily be recovered from the solvent solution thereof by distillation under reduced pressure. The semi-concentrate will be found to be devoid of free fatty acids and much lighter in color than the original oil and substantially free of undesirable tastes and odors.

The next step in the process of the invention is to contact the semi-concentrate with a solvent which is characterized by being miscible with the semi-concentrate at temperatures about room temperature, and partially immiscible therewith at temperatures below room temperature. The solvent employed in this step may be selected from a large number of aliphatic solvents found to be useful as a result of extensive experimentation; the choice of the solvent will depend to some extent upon the properties of the semi-concentrate to be treated, as will become more evident from the detailed description hereinafter given. Results have indicated that the solvents preferably employed are members of well recognized chemical classes; it has also been found that the number of carbon atoms in the solvent to be used is a particularly important factor in determining the availability thereof for use in the practice of this invention. The following table sets forths, the classes of solvents which have been found to be particularly useful in the practice of this invention:

Table

1. Aliphatic and alicyclic monohydroxy alcohols containing from 3 to 6 carbon atoms.
2. Esters formed by the reaction of aliphatic and alicyclic alcohols with aliphatic monocarboxylic acids, said esters containing not more than 8 carbon atoms.
3. Aliphatic and alicyclic aldehydes containing not more than 6 carbon atoms.
4. Aliphatic ketones containing not more than 6 carbon atoms.

Solvents falling in the classes above listed are all liquid polar aliphatic organic compounds having the properties of being miscible with marine oils or partially saponified fractions thereof at temperatures above room temperature, i. e. 20° to 25° C., and partially immiscible therewith at temperatures substantially below room temperature, and it has been found that solvents falling within this class of compounds may be used in the practice of this invention. In addition it will be noted that the preferred solvents possess relatively low freezing points.

In order to more fully illustrate the nature of the solvents which may be employed, a partial list thereof is herewith given; it is to be understood, however, that this list is not intended to be complete, but is merely illustrative of the solvents which may be employed. Thus it has been found that the following solvents may be used: n-propyl alcohol, isopropyl alcohol, n-butyl alcohol, n-amyl alcohol, isomyl alcohol, secondary amyl alcohol, furfuryl alcohol, allyl alcohol, diacetone alcohol, β -hydroxy ethyl acetate, methyl formate, ethyl formate, ethyl acetate, methyl acetate, isopropyl acetate, glycol formate, glycol diacetate, methyl levulinate, ethyl levulinate, methyl aceto-acetate, ethyl aceto-acetate, methyl furoate, vinyl acetate, furfural, propionaldehyde, crotonaldehyde, acetone, methyl ethyl ketone, acetonyl, acetone, propylene chlorhydrin and acetic anhydride. Mixtures of these solvents may also be used. It will be noted that all these solvents belong to that class of aliphatic organic compounds which have the properties of being miscible with marine oils and partially saponified marine oils at temperatures above room temperature and partially immiscible therewith at temperatures substantially below room temperature; furthermore, it will be noted that the majority of these solvents have relatively low freezing points.

Occasionally it may be found that certain of the solvents hereinabove mentioned may be too miscible with some semi-concentrates which may be treated by this invention to effect a separation of highly potent vitamin fractions therefrom; thus, for example, acetone is too miscible with some semi-concentrates to accomplish the purposes of this invention. However, this condition may be easily corrected by diluting the solvent either with a small amount of water or with a liquid aliphatic organic solvent relatively immiscible with marine oils. In general it may be said that the effect of diluting any of the above solvents with water will be to render the solvents more immiscible with marine oils or fractions thereof, so that if difficulty is encountered in effecting proper separation of the highly potent extracts from the semi-concentrate, this difficulty may generally be overcome by the addition of a small amount of water to the solvent.

The solvents preferably employed in the practice of the invention are the aliphatic alcohols containing from 3 to 6 carbon atoms; of these solvents isopropanol and diacetone alcohol have proved to be the most successful.

In carrying out the extraction of the semi-concentrate with the polar solvent, the unsaponified fraction is first mixed with the particular solvent to be employed. The relative proportion of the semi-concentrate to solvent in the mixture may vary widely; preferably the ratio of solvent to the concentrate should be greater than one and in most cases mixtures containing between about 2% and about 25% of the concentrate are most suitable. This mixture may then be heated until the semi-concentrate or the greater part thereof is dissolved in the solvent. The temperature to which the mixture is heated may vary widely depending upon the nature of the ingredients contained in the mixture; in general it may be stated that it is inadvisable to heat fat-soluble vitamin-containing materials to temperatures in excess of 175° C. because of the relative instability of vitamin A at temperatures above this point. It is preferred to form the solution of semi-concentrate in the solvent by first heating the solvent to

be used to a predetermined temperature at which the concentrate to be added will substantially completely dissolve in the solvent, and then adding the concentrate to the solvent with agitation, the operation being carried out in an inert gas atmosphere.

The solution of the semi-concentrate in the solvent prepared as hereinabove described may then, in accordance with the process of the invention, be permitted to cool so as to effect a separation of the solution of the highly potent vitamin extract from the remainder of the concentrate. The temperature to which the solution is cooled may vary from about room temperature to as low as -70° C. or lower. It has been found, however, that it is preferable to cool the solution with agitation to temperatures somewhat below about 0° C., e. g. in the neighborhood of about -18° C. Upon cooling the solution separates into two layers. One layer consists chiefly of the portion of the semi-concentrate insoluble in the solvent at low temperatures. The vitamin content of this fraction is much less than that of the semi-concentrate. This fraction has a considerably lighter color than the semi-concentrate and also has lost the characteristic odor possessed by many fat-soluble vitamin-containing oils.

The solvent layer obtained upon cooling the solution may be filtered and then treated to remove the solvent therefrom, e. g. by vacuum distillation, whereby a concentrate is recovered having a vitamin content far in excess of the amount contained in the original semi-concentrate; the percentage increase in vitamin potency may be anywhere between about 100% and about 600%, the actual increase varying with the vitamin potency of the semi-concentrate.

The process of the invention may also be carried out by continuously contacting the semi-concentrate with one of the above polar solvents at a relatively low temperature, e. g. around 0° C.; this method of operation effects a continuous extraction of a highly potent vitamin fraction from the concentrate. However, it is preferred to employ the batch method hereinabove described.

The resulting high potency concentrate may, after the removal of solvent therefrom, be further extracted with methanol and/or ethanol to free the concentrate of the vitamin alcohols present therein thus providing a high potency concentrate substantially free of vitamin alcohols.

For a fuller understanding of the nature and objects of the invention, reference should be had to the following examples which are given merely to further illustrate the invention and are not to be construed in a limiting sense, all parts given being by weight, and all vitamin potencies being expressed in U. S. P. units:

Example I

60 200 parts of shark liver oil having a potency of 103,000 units of vitamin A per gram, 100 parts of ethylene dichloride and 6 parts of isopropanol were admixed with sufficient 46% aqueous potassium hydroxide to saponify about 50% of the shark liver oil. The mass was stirred at room temperature in the presence of N₂ gas for about thirty minutes whereby a super-solvent soap emulsion was formed. The mass was allowed to stand overnight, and then 700 more parts of ethylene dichloride were added thereto, and the mass heated to a temperature of about 60° to 70° C. The solvent-soap mass was cooled to room temperature and the moisture content of the soap adjusted to about 25%. The solvent separated out from the soap mass carrying with it the un-

saponified oil. The soap mass was extracted two more times with ethylene dichloride employing four parts of solvent to one part of soap. The solvent extracts were combined, filtered, and the solvent removed therefrom. The unsaponified oil which was recovered had a potency of 200,000 units of vitamin A per gram and contained substantially all of the vitamin A which had been present in the original oil.

This unsaponified oil was then extracted three times with 99% isopropanol by admixing the oil and isopropanol at a temperature slightly above room temperature so that the solvent and oil became completely miscible, then cooling the solution to about -18°C., and separating the solvent layer containing a highly potent vitamin fraction from the oil immiscible with the solvent at the low temperature. No difficulty was encountered in separating the solvent layer from the oil layer during any of the three extractions. The solvent extracts were combined and the solvent removed therefrom. A light golden yellow colored extract having a potency of 406,000 units of vitamin A per gram and containing over 60% of all the vitamin A which was present in the original oil was obtained. The taste and odor of the extract was greatly superior to the taste of extracts prepared by solvent extracting the original oil.

A sample of the original oil was similarly extracted three times with isopropanol. However, only about 37% of the vitamin A contained in the oil was recovered and the potency of the combined extracts was only about 215,000 units of vitamin A. These results clearly illustrate the great superiority of the process of the present invention.

Example II

A crude shark liver oil was partially selectively saponified similarly as in Example I except that about 60% of the oil was saponified. The following analyses of the crude oil and the unsaponified oil recovered from the partially saponified mass illustrate the improvement in quality obtained by means of the partial saponification and also explain to a certain extent why the unsaponified oil may be so much more readily extracted with a polar solvent to produce improved concentrates.

	Crude oil	Partially saponified oil
Percent free fatty acid.....	5.1	0.1
Color (Lovibond):		
Red.....	49	10.3
Yellow.....	90	18
Iodine value.....	135	154
Cloud point..... ° F	59	44
Pour point..... ° F	45	32
Vitamin A potency..... units/gm.	63,000	147,500

The oil recovered from the partially saponified mass was much more satisfactory with regard to taste and odor than the crude oil, and, as may be seen by referring to the analyses, was much lighter in color than the crude oil. The higher iodine value and lower cloud and pour points of the oil recovered from the partially saponified mass show that stearins and other high melting components which interfere with the solvent extraction have been eliminated. Furthermore the recovered oil is almost completely devoid of free fatty acids, which acids would tend to lessen the efficiency of the solvent extraction if they were present.

After recovering the unsaponified oil from the

partially saponified mass, the unsaponified oil was extracted with isopropanol similarly as in Example I except that only two extractions were made. No difficulty at all was encountered in making these extractions; only about 4% of the solvent was entrained in that part of the oil immiscible with the solvent at the low temperature. A fraction having a potency of 268,000 units of vitamin A per gram was obtained as compared with a potency of 103,000 units of vitamin A per gram when a fraction was prepared similarly by extracting the crude oil itself with isopropanol. Furthermore the total yield of vitamin A when the crude oil was extracted directly was only one-third that obtained by extracting the unsaponified oil recovered from the partially saponified mass. Whereas about 96% of the solvent was recovered along with the extract when the unsaponified oil recovered from the partially saponified mass was extracted with solvent, only about 24% of the solvent was recovered with the extracts when the crude oil was extracted, the remaining 76% of the solvent being entrained in the residue of the crude oil.

Example III

Tuna liver oil having a potency of 73,000 units of vitamin A per gram was partially saponified about 50% similarly as in the previous examples. Samples of the original oil and of the oil recovered from the partially saponified mass were extracted with isopropanol as in the other examples. In the first case, the extract recovered had a potency of only 137,000 units of vitamin A but in the latter case an extract having a potency of 239,000 units of vitamin A was obtained. The greatest difficulty of separation of the solvent from the oil and the poorest recovery of solvent accompanied by a consequently poorer vitamin recovery was encountered with the extraction of the original oil directly.

Example IV

200 parts of shark liver oil containing 103,000 units of vitamin A per gram, 9% of the vitamin being in the alcohol form and the remaining 91% being in the ester form, were mixed with 100 parts of ethylene dichloride and 6 parts of isopropanol. While stirring in the presence of N_2 gas, sufficient 45% aqueous KOH (39.4 gms.) to saponify about 50% of the oil was added and the stirring continued for about 15 minutes. The thick soap mass was then insulated and left at room temperature for about 12 hours. 800 parts of ethylene dichloride were added and the solvent-soap mass heated to about 60°C. while stirring for about 15 minutes. Sufficient water was added at this stage to increase the moisture content of the soap to about 24%. The entire solvent-soap mass was then cooled to about 25°C. and the stirring ceased. After about 15 minutes, the lower solvent layer was drawn-off and the soap extracted 6 more times as before. The solvent extracts were combined, filtered and the solvent evaporated under reduced pressure at a low temperature in the presence of N_2 gas. The recovered partially saponified oil contained 187,000 units of vitamin A per gram and was substantially devoid of free fatty acids and was lighter in color and free of the original fishy taste and odor.

90 parts of the partially saponified oil containing 187,000 units of vitamin A per gram were mixed with 360 parts of 99% isopropanol and the mixture warmed to about 36°C. to give a clear

solution. The isopropanol-oil solvent was then cooled gradually to about -18°C . After 12 hours, the upper solvent layer was removed and filtered. The insoluble solid oil fraction was then extracted again with a similar quantity of isopropanol. The clear filtrates were combined and the isopropanol removed under reduced pressure in the presence of N_2 gas. The resulting concentrate contained 358,000 units of vitamin A per gram and possessed only a slightly fishy taste and odor. The free fatty acid content was 0.28% as compared to 1.5% for the original crude shark liver oil.

10 parts of the high potency isopropanol soluble concentrate containing 358,000 units of vitamin A per gram were mixed with 40 parts of 95% ethanol and the mixture warmed to about 50°C . The mixture was then cooled gradually to about -25°C . and filtered. The insoluble oil layer was removed and extracted similarly 3 more times. The combined ethanol filtrates were removed and the ethanol evaporated at a low temperature under reduced pressure in the presence of N_2 gas. The recovered oil possessed a fishy taste and odor and contained 475,000 units of vitamin A per gram. The vitamin A was largely in the alcohol form and represented 10% of the amount present in the starting material. The ethanol insoluble oil layer was freed of entrained solvent in the manner just described. The recovered oil was light yellow in color, completely without taste and odor, and contained 340,000 units of Vitamin A per gram, the vitamin A being in the ester form and comprising 90% of that present in the original isopropanol soluble concentrate.

It is evident from the above description and examples that my invention provides a highly improved process for producing highly potent ester concentrates of the fat-soluble vitamins. The vitamin ester concentrates produced by this process are much more potent than such concentrates produced by extracting the original oil directly and are also much more potent than the concentrates obtained merely by selectively saponifying the oil. Furthermore, since from 30% to 60% of the fatty material is eliminated before carrying out the solvent extraction, a much lesser quantity of fatty material has to be extracted than when treating the original oil. Not only does this result in an increased saving in the amount of solvent which is required, but also the amount of equipment necessary to prepare the concentrates is greatly reduced from that which would be required if the concentrates were prepared by extracting the original oil. The fact that that portion of the semi-concentrate which is immiscible with the solvent at the low temperature does not tend to entrap the solvent, as in the case of the original oil, further lessens the amount of solvent which is required and at the same time results in greatly increased efficiency in extracting the vitamins. The highly desirable characteristics of the concentrates which are obtained as regards color, taste and odor, further add to the desirability of the process as compared to prior processes for producing vitamin concentrates.

While the only specific method of effecting saponification (hydrolysis) of the esters contained in marine oils has involved the use of an alkaline agent, other methods to effect splitting of the esters may be employed within the purview of this invention and particularly enzyme saponification (hydrolysis).

Since certain changes may be made in carrying out the above process without departing from the scope of the invention, it is intended that all matter contained in the above description shall be interpreted as illustrative and not in a limiting sense.

Having described my invention, what I claim as new and desire to secure by Letters Patent is:

1. A process of producing a fat-soluble vitamin ester concentrate, which comprises saponifying 10% to 60% of the glycerides present in a fat-soluble vitamin-containing marine oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature, cooling the mass to a temperature within the range of 0°C . to -70°C . to cause layer formations and separating the solvent layer containing the extracted vitamins from the solvent-insoluble portion of said fraction.
2. A process of producing a fat-soluble vitamin ester concentrate, which comprises saponifying 30% to 50% of the glycerides present in a fat-soluble vitamin-containing marine oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature, cooling the mass to a temperature within the range of 0°C . to -70°C . to cause layer formations and separating the solvent layer containing the extracted vitamins from the solvent-insoluble portion of said fraction.
3. A process of producing a fat-soluble vitamin ester concentrate, which comprises saponifying 10% to 60% of the glycerides present in a fat-soluble vitamin-containing marine oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature, cooling the mass to a temperature within the range of 0°C . to -70°C . to cause layer formations, separating the solvent layer containing the extracted vitamins from the solvent-insoluble portion of said fraction.
4. A process of producing a fat-soluble vitamin ester concentrate, which comprises saponifying 10% to 60% of the glycerides present in a fish liver oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature, cooling the mass to a temperature within the range of 0°C . to -70°C . to cause layer formations and separating the solvent layer containing the extracted vitamins from the solvent-insoluble portion of said fraction.

5. A process of producing a fat-soluble vitamin ester concentrate, which comprises saponifying 30% to 50% of the glycerides present in a fish liver oil, separating the unsaponified fraction from the saponified matter, contacting the unsaponified fraction with an organic aliphatic polar solvent which is characterized by being miscible with the unsaponified fraction at temperatures above room temperature and partially immiscible therewith at temperatures below room temperature, cooling the mass to a temperature within the range of 0° C. to -70° C. to cause layer formations and separating the solvent layer containing the extracted vitamins from the solvent-insoluble portion of said fraction.

6. A process of producing a fat-soluble vitamin ester concentrate, which comprises saponifying 10% to 60% of the glycerides present in a fat-soluble vitamin-containing marine oil, separating the unsaponified fraction from the saponified matter, contacting the unsaponified fraction with isopropanol, cooling the mass to a temperature within the range of 0° C. to -70° C. to cause layer formations and separating the isopropanol layer containing the extracted vitamins from the isopropanol-insoluble portion of said fraction.

7. A process of producing a fat-soluble vitamin ester concentrate, which comprises saponifying 30% to 50% of the glycerides present in a fat-soluble vitamin-containing marine oil, separating the unsaponified fraction from the saponified matter, contacting the unsaponified fraction with isopropanol, cooling the mass to a temperature within the range of 0° C. to -70° C. to cause layer formations, separating the isopropanol layer containing the extracted vitamins from the isopropanol-insoluble portion of said fraction, re-

moving the isopropanol from the extracted vitamins and removing the vitamin alcohols therefrom by extraction with a solvent selected from the group consisting of methanol and ethanol.

5 8. A process of producing a fat-soluble vitamin ester concentrate, which comprises saponifying 10% to 60% of the glycerides present in a fat-soluble vitamin-containing marine oil, separating the unsaponified fraction from the saponified matter, contacting the unsaponified fraction with isopropanol, cooling the mass to a temperature within the range of 0° C. to -70° C. to cause layer formations, separating the isopropanol layer containing the extracted vitamins from the isopropanol-insoluble portion of said fraction, removing the isopropanol from the extracted vitamins and removing the vitamin alcohols therefrom by extraction with a solvent selected from the group consisting of methanol and ethanol.

10 15 20 25 30 35 9. A process of producing a fat-soluble vitamin ester concentrate, which comprises dissolving in a fish liver oil 25% to 75% (based on the weight of the oil) of a non-polar solvent, saponifying 10% to 60% of the glycerides present in said oil, separating the unsaponified fraction from the saponified matter, contacting the unsaponified fraction with isopropanol, cooling the mass to a temperature within the range of 0° C. to -70° C. to cause layer formations, separating the isopropanol layer containing the extracted vitamins from the isopropanol-insoluble portion of said fraction, removing the isopropanol from the extracted vitamins and removing the vitamin alcohols therefrom by extraction with a solvent selected from the group consisting of methanol and ethanol.

LORAN O. BUXTON.
